Primary Examiner — Christy Nemeth(74) *Attorney, Agent, or Firm* — McCormick, Paulding & Huber PLLC(57) **CLAIM**

The ornamental design for a frequency converter, as shown and described.

DESCRIPTION

FIG. 1 is a front, right side and top perspective view of a frequency converter comprising a new, original and ornamental design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines illustrate portions of the frequency converter that form no part of the claimed design.
